(57) **CLAIM**

The ornamental design for a bubble wand, as shown and described.

DESCRIPTION

FIG. 1 is a front elevational view of a bubble wand, showing our new design.

FIG. 2 is a left elevational view thereof.

FIG. 3 is a right elevational view thereof.

FIG. 4 is a top plan view thereof.

FIG. 5 is a bottom plan view thereof.

FIG. 6 is a rear view thereof; and,

FIG. 7 is a perspective view showing the design as it appears with the hand opening in an expanded state.
